Primary Examiner — Catherine R Oliver-Garcia

(57) **CLAIM**

The ornamental design for a mobile phone armband, as shown and described.

DESCRIPTION

FIG. 1 is a perspective view of a mobile phone armband showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view of the mobile phone armband where a phone holder is separated from a mobile phone armband body;

FIG. 10 is another perspective view of the mobile phone armband where the phone holder is separated from the mobile phone armband body;

FIG. 11 is an enlarged view of portion 11 shown in FIG. 1;

FIG. 12 is an enlarged view of portion 12 shown in FIG. 1;

FIG. 13 is an enlarged view of portion 13 shown in FIG. 1;

FIG. 14 is an enlarged view of portion 14 shown in FIG. 1; and,

FIG. 15 is an enlarged view of portion 15 shown in FIG. 3. The broken lines in the drawings depict portions of the mobile phone armband that form no part of the claimed design.

1 Claim, 15 Drawing Sheets
